UNITED STATES PATENT OFFICE

2,656,838

COLOSTOMY UNIT

Glenn McConnell, Pontiac, Mich., assignor of
one-third to Melba McConnell, Pontiac, Mich.

Application October 24, 1952, Serial No. 316,721

6 Claims. (Cl. 128—283)

1

This invention comprises novel and useful improvements in a colostomy unit and more specifically pertains to a colostomy appliance in which the colostomy bag is removably secured in a readily detachable manner, and wherein all the parts of the device may be readily disassembled for efficient sterilizing, cleaning or servicing of the same.

The primary object of this invention is to provide a colostomy unit which shall receive discharge from body orifices such as the colon after surgical operations or the like, with provision for establishing an improved leak-proof sealing engagement of the colostomy bag with the body orifice.

A further object of the invention is to provide an appliance in conformity with the preceding objects wherein an improved attachment of the colostomy bag to the supporting structure of the device is obtained, and wherein a shield or guard is provided for protecting the attachment of the bag to the device; and wherein means is provided for maintaining the neck of the bag open to permit effective discharge from a body orifice into the bag.

Yet another important object of the bag is to provide a colostomy appliance as set forth in the preceding objects which shall have a comfortable and improved sealing engagement of the same upon the body of a patient without however, sacrificing efficiency of operation of the device or efficiency of a sealing engagement of the device with the body of a patient.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view showing a colostomy appliance incorporating therein the principles of this invention, the device being shown in the position in which it is applied to the body of a patient for use;

Figure 2 is a fragmentary vertical transverse sectional detail view taken substantially upon the plane indicated by the section line 2—2 of Figure 1 and showing in particular the manner in which the colostomy bag is removably secured to the device and showing the improved sealing means of the device;

Figure 3 is an exploded perspective view of certain elements of the device, the colostomy bag

2

and the supporting belt being omitted therefrom;

Figures 4 and 5 are respectively horizontal sectional detailed views taken substantially upon the planes indicated by the section lines 4—4 and 5—5 of Figure 3 and disclosing the bag retaining member with a bag distending hood thereon and a plate having a bag protecting shield applied thereto; and,

Figure 6 is a perspective view taken from the rear of the bag retaining means of Figure 4.

Referring now more specifically to the accompanying drawings, it will be seen that the colostomy unit or appliance in accordance with this invention includes a supporting strap or belt 10 which may conveniently be provided with a conventional buckle or fastening assembly whereby the belt may be adjusted to comfortably embrace the body of a patient, the belt having a pair of adjacent end portions provided with snap fastener eyelets 14, by which the belt is removably secured to the other elements of the appliance for supporting the latter upon the body of a patient adjacent a body discharge orifice such as the colon.

The colostomy appliance supported by the belt 10 includes plate 16 of any suitable material such as plastic, metal or the like and which is preferably suitably contoured to conveniently and comfortably conform to the body of a patient adjacent a body orifice to which the device is to be applied. At its opposite sides, the plate 16 is provided with snap fasteners 18 which cooperate with the eyelets 14, previously mentioned, whereby the plate 16 may be detachably secured to the supporting belt. The plate 16 includes a centrally disposed opening 20 which is adapted to be positioned adjacent a body orifice and which is of a size to accommodate the neck portion 22 of a colostomy bag 24 which may be of cellophane or any other suitable material.

Detachably carried by the plate 16 is an arcuate or dish-shaped shield 26 of plastic or any other suitable material, which is adapted to extend through the opening 20 of the plate 16 and beyond what may be termed the front side of the plate in a manner to overlie and cover the upper portion of the neck 22 of the colostomy bag where the neck portion is attached to the plate as set forth hereinafter. The shield 26 is mounted upon an annular ring or flange 28 which is adapted to seat against the rear face of the plate 16 upon the rim of the orifice 20. It is contemplated that a resilient or snap fit shall be provided between that portion of the shield 26 which joins the annular ring 28, thereof, and the inside periphery of the opening 20 whereby

the guard member 26 may be pushed through the opening from the rear face of the plate and frictionally held therein.

As will be best apparent from Figure 2, the open end of the neck portion 22 of the colostomy bag 24 extends underneath the shield 26 and through the opening in the ring 28 of the shield, and thus through the opening 20 in the plate 16 and is then folded outwardly upon the ring 28 and upon the back side of the plate 16 where it is retained in a manner to be now set forth.

This retaining means consists of an assembly which may be of plastic or any other suitable material, and includes a disk-like member 30 having an annular flange 32 upon which is secured a guard 34 which is of substantially the same configuration as the shield 26. The member 30 upon which may be termed its rear face is provided with an annular boss 36, and has an opening 38 which extends through the boss and the member. The opening 38 is disposed concentrically with respect to the opening 20 and the opening of the ring 28, as will be readily apparent from the Figure 2.

The proportions of the retaining member are such that the same may be inserted from the rear of the plate 16 through the opening 20 thereof and will have a snap or resilient engagement with the opening through the ring 28. As shown in Figure 2, the retainer when so inserted will have its flange 32 bearing tightly against the outfolded open end of the neck 22 of the colostomy bag 24 for pressing the same against the rear surface of the flange 28.

Sealing means are provided for comfortably applying the plate 16 to the body portion of a patient and for preventing any leakage about the colon or other discharge orifice of a patient. For that purpose, there is provided a pad 40 having a central opening 42 therein, which pad as shown in Figure 2 is applied to the back face of the plate 16 and overlies and rests upon the out-turned end of the opened neck of the colostomy bag and presses the same against the rear face of the plate. The pad 40 which may be of sponge rubber or any other suitable yieldable material thus comfortably seals upon the skin of the patient and establishes an effective sealing engagement between the plate 16 and about the orifice of a patient.

A further sealing member in the form of a washer or ring 44 is provided having a central aperture 46 therein. The ring 44 is mounted upon the boss 36 and seats against the rear face of the retainer 30, and is frictionally received within the opening 42 of the pad 40.

As seen in Figure 2, the sealing members 40 and 44 thus establish an effective and leak-proof seal about the patient's orifice and the openings 38, 20 and 28.

It will thus be apparent that there has been provided a device by means of which a colostomy bag may be readily applied to or removed from the unit, and wherein all the parts of the same may be quickly disassembled to insure effective sterilization of the same. The device protects the neck portion of the colostomy bag and holds the same in an open position to render its use most satisfactory.

What is claimed as new is as follows:

1. A colostomy appliance comprising a plate, a belt adapted to embrace the body of a patient, fasteners detachably securing said belt to opposite sides of said plate, said plate having an opening adapted to be disposed in registry with

a body discharge orifice of a patient, a colostomy bag disposed on the front of said plate and having a neck portion extending through said opening, a retaining means on the back of said plate having a snap engagement with the rim of the plate opening and clamping the neck portion to said plate, said retaining means having a hood extending through the plate opening and into the neck portion and distending said neck portion.

2. A colostomy appliance comprising a plate, a belt adapted to embrace the body of a patient, fasteners detachably securing said belt to opposite sides of said plate, said plate having an opening adapted to be disposed in registry with a body discharge orifice of a patient, a colostomy bag disposed on the front of said plate and having a neck portion extending through said opening, a retaining means on the back of said plate having a snap engagement with the rim of the plate opening and clamping the neck portion to said plate, said retaining means having a hood extending through the plate opening and into the neck portion and distending said neck portion, said plate having a shield on its front overlying and protecting the neck portion of said bag.

3. A colostomy appliance comprising a plate, a belt adapted to embrace the body of a patient, fasteners detachably securing said belt to opposite sides of said plate, said plate having an opening adapted to be disposed in registry with a body discharge orifice of a patient, a colostomy bag disposed on the front of said plate and having a neck portion extending through said opening, a retaining means on the back of said plate having a snap engagement with the rim of the plate opening and clamping the neck portion to said plate, said retaining means having a hood extending through the plate opening and into the neck portion and distending said neck portion, said plate having a shield on its front overlying and protecting the neck portion of said bag, said shield and said hood being disposed in closely spaced nested relation.

4. A colostomy appliance comprising a plate, a belt adapted to embrace the body of a patient, fasteners detachably securing said belt to opposite sides of said plate, said plate having an opening adapted to be disposed in registry with a body discharge orifice of a patient, a colostomy bag disposed on the front of said plate and having a neck portion extending through said opening, a retaining means on the back of said plate having a snap engagement with the rim of the plate opening and clamping the neck portion to said plate, said retaining means having a hood extending through the plate opening and into the neck portion and distending said neck portion, said plate having a shield on its front overlying and protecting the neck portion of said bag, said shield having a peripheral flange removably seated upon the rim of said plate opening upon the back of said plate.

5. A colostomy appliance comprising a plate, a belt adapted to embrace the body of a patient, fasteners detachably securing said belt to opposite sides of said plate, said plate having an opening adapted to be disposed in registry with a body discharge orifice of a patient, a colostomy bag disposed on the front of said plate and having a neck portion extending through said opening, a retaining means on the back of said plate having a snap engagement with the rim of the plate opening and clamping the neck portion to said plate, said retaining means having a hood extending through the plate opening and into the neck portion and distending said neck portion, said plate having a shield on its front overlying and protecting the neck portion of said

bag, said shield being removably carried by said plate.

6. A colostomy appliance comprising a plate, a belt adapted to embrace the body of a patient, fasteners detachably securing said belt to opposite sides of said plate, said plate having an opening adapted to be disposed in registry with a body discharge orifice of a patient, a colostomy bag disposed on the front of said plate and having a neck portion extending through said opening, a retaining means on the back of said plate having a snap engagement with the rim of the plate opening and clamping the neck portion

to said plate, an apertured sealing pad of yieldable material disposed on the back of said plate, an apertured sealing disk disposed in the aperture of said sealing pad.
